IONIC AMPLIFIER

Samuel Ruben, New Rochelle, N. Y.

Application December 16, 1933, Serial No. 702,667

18 Claims. (Cl. 250—27.5)

This invention relates to an ionic discharge amplifier.

This application may be said to be a continuation in part of my applications bearing Serial 5 Numbers 634,994, filed September 27, 1932; 641,334 filed November 5, 1932, and 669,503 filed May 5, 1933, relating to grid controlled ionic amplifiers.

An object of the invention is the provision of 10 an ionic discharge device capable of being used as an amplifier and specifically to provide a device capable of being used as a power detector in a radio receiving circuit without the requirement of an auxiliary audio amplifier.

Another object is to provide a means of obtaining a sensitive or graduated control of an 15 ionic discharge throughout the entire current output range.

A specific object is to obtain such a control 20 electrostatically by the use of an initially negatively biased grid element and with minimum grid current flow.

A further object is the provision of an amplifier 25 device in which the higher power output obtainable by the use of an ionized metal vapor such as mercury or mercury amalgam can be controlled by an electron discharge within the amplifier device.

An object is to provide an electrical discharge 30 tube allowing a load impedance and a power output and sensitivity greater than that obtainable from vacuum type amplifier tubes of comparable structure.

A specific object is to provide an electrical 35 discharge tube having an atmosphere of restricted vapor pressure and in which the mean free path length is greater than the distance between the cathode and control element.

An object of this invention is to provide in an 40 electron discharge tube a limited vapor atmosphere insufficient to allow conduction within certain areas by ionic conduction, but sufficient to allow a reduced electron space charge.

Still another object is to employ in tubes of 45 the type described an atmosphere which is the resultant product of two materials one having a relatively low vapor pressure, for instance, cadmium, and one having a relatively high vapor pressure such as mercury, the ratio of composition being such as to prevent an excessive rise of pressure which might tend to cause an arc-like discharge under operating conditions. Such arc-like discharges are caused by ionic bombardment in devices where the pressure is such that the mean free path length is less than the distance 50 between the elements maintained at a potential difference.

Other objects will be apparent from the disclosure and from the drawing in which,

Fig. 1 shows a tube of the invention in an 55 operable circuit, and

Fig. 2 is a top view, showing the arrangement of the elements.

The tube may also be used in other circuits and for such other uses as combined oscillator and detector, audio and radio frequency amplifier, voltage amplifier in connection with such devices as photo cells, relays, etc. 5

The tube physically comprises an electron emission cathode, an anode, an ionizable medium, a control grid surrounding the cathode, a shield 10 or space charge grid surrounding the control grid, a third grid surrounding the shield grid and facilities at the terminals of the electron emission areas for confining the discharge directly to the space between the cathode and anode through 15 the grids. The spacings between the tube elements are of fundamental importance; are dependent upon such factors as vapor pressure and mean free path length and control the operation and effectiveness of the tube. 20

In general, the device operates with a direct electrostatic control of an electron discharge with means of shielding the control electrode from an 25 ionic discharge resulting from impact of the controlled electron discharge with the vapor atmosphere.

In thermionic discharge tubes of the prior art employing a thermionic cathode in a space charge reducing atmosphere such as mercury, only a trigger type of control is obtained. Once the current flow starts, the grid has little influence on the discharge, the change in grid voltage merely varying the thickness of the sheath of positive ions surrounding the grid. Where the grid supply potential variations are of a practical order, 30 the plate potential must be disrupted to extinguish the discharge. The trigger potential is determined by the initial amplification factor of the tube. This "trigger" characteristic has prevented the use of tubes of this type in circuits such 35 as shown in the drawing or in other audio amplifier circuits requiring a graduated or non-distorted amplification of an applied control potential to the grid control element. 40

Furthermore, in such grid controlled tubes, only 45 a very low plate potential such as a maximum of fifteen volts is applied to the plate, whereas in the tube of my invention, much higher voltages, such as in the order of two hundred volts or more, may be applied to the plate. 50

In the present tube a complete graduated and sensitive control equivalent to that had in a pure electron type of discharge is obtained. In this tube the electron discharge surrounding the cathode is directly controlled by a grid located close 55 to the cathode, preferably within the "cathode fall space", at a distance less than the mean free path length of the electrons in the ionizable medium. The control grid is surrounded by a positively charged grid which serves a two-fold 60

purpose: It tends to lower the impedance and space charge and reduces the migration of positive ions to the control grid.

Generally speaking, it may be said that up to 5 this point the present tube is somewhat similar to that described in my co-pending application bearing Serial Number 669,503.

However, the tube of this invention differs from the tubes described in my co-pending applications. Instead of having a fairly definite limit at which the control grid may be placed from the cathode, as represented by the cathode fall space described in the prior applications, the area of controllable electron discharge adjacent 15 to the cathode has been extended. This allows a more practical structure and has the effect of reducing sputtering of the elements.

This extension of the electron discharge or electrostatically controllable area has been accomplished by the use of a material having a vapor pressure much lower than the mercury utilized in my prior tubes and by employing two grids surrounding the control grid. A factor of importance is that the third grid tends to further 20 reduce ionic current flow to the control grid. Such ionic flow would tend to render the control grid inefficient (electrostatically).

It may be said that the tube of this invention is preferably a detector and that the tubes of 30 my two preceding applications referred to are primarily amplifiers.

As in the tubes of my co-pending applications above referred to, the surrounding anode may be located at a distance beyond the cathode fall 35 space or at a distance greater than the mean free path length of the electrons in the ionizable medium; also as in my other tubes, the discharge is confined directly to the space between the cathode and anode, through the grids.

40 When looking downward in the tube, (when operating) it is observed that the area between the cathode and control grid is dark; that the area between the control grid and the second grid (first positively charged grid) is dark with 45 negligible visible discharge; that there may be a faint luminosity in the area between the second and third grids, but that the area between the third or outer grid and the anode, is highly luminous, due to the increased ionization of the vapor 50 in this space. Thus, the control grid is operated in a relatively ion free atmosphere, as can be further noted from low grid current flow when biased negatively, and the smooth and stepless control of the plate current output. If the potential on the positively charged second grid 55 should be raised beyond a critical value, probably represented by the sum of the ionization potential of the gas and the field voltage drop across the preceding grid or grids, intense or localized 60 ionization can occur in the space between the cathode and the grids, with change from a dark to a luminous area. Substantial ionization in the space surrounding the control grid makes its control ineffective.

65 The relative luminous effects noted in this tube are not due to means used in the prior art, where, for example, a self supporting discharge was used with a control grid located in the cathode dark space, or where screens have been used to separate the discharge into two definite classes. The negligible amount of ionization in my tube near the cathode is due to the use of an electrode distance less than the electron mean free path 70 length which with the spacial relations used is

obtained by use of the cadmium amalgam as a source of ionizing medium.

From the foregoing, it is to be noted that certain fundamental factors are essential in relation to the tube and its circuit. These may be 5 stated as:

1. The potential applied to the second grid should be less than is necessary to intensely ionize the space between it and the cathode and is determined by the combined effect of ionization potential of the gas, the gas pressure and the field voltage gradient across the first grid. 10

2. That the potential applied to the second grid should not be of such a magnitude as to force a localized ionic discharge from it to the 15 cathode through the control grid.

3. A third grid, to assist in reducing electron impedance and further shield the control grid from the ionic sheath, is necessary.

4. That the source of an ionizable medium or 20 vapor should not have a large pressure rise with temperature and should be such that the mean free path length of the electrons in the ionizable medium under all operating conditions is greater than the distance between the control electrode 25 and the cathode or the space between the grids. The ionizable medium should have limited or restricted maximum pressure rise.

The three grids should preferably be as close as practicable. It is desirable that they should have 30 approximately the same number of turns.

In order to reduce sputtering of the grids due to ionic impact, I have found it desirable to coat the grids with a material having a low atomic number, such as beryllium, carbon or 35 aluminum. One of the most practical methods is to coat the grids with deflocculated graphite to which has been added about twenty per cent aluminum powder. The latter prevents scaling or peeling of the graphite coating, probably due 40 to its leaflike structure and expansion factor.

In order to prevent the tube from becoming inoperative or "running away" due to temperature rise and resultant increase in vapor pressure as when mercury is used, and to allow a mean free 45 path length greater than the space between the control electrodes, I have found it very desirable to use an amalgam of mercury and cadmium in place of the straight mercury. As the cathode fall space varies with the internal atmosphere 50 pressure (see my co-pending application bearing Serial Number 669,503) as does also the free mean path length, unless a means is provided to prevent the large rise in vapor pressure of the mercury in the tube, due to the heating caused 55 by the cathode and plate energy dissipation, or unless an external cooling means is provided, the tube will become inoperative with an arc-like discharge between cathode and anode and no control will be had. By use of a cadmium-mercury 60 amalgam, a smaller bulb can be used and the starting time cut to a fraction of what it would be with pure mercury. In addition, with a proper proportion of cadmium, the pressure does not rise to excess value under any operating condition. 65 The cadmium-mercury amalgam being in a hard solid form, is chemically stable and easy to handle.

I have used other mercury amalgams such as the alkaline amalgams sodium and potassium. While these tend to hold down the vapor pressure 70 in the tube, they are difficult to handle. They do no sufficiently hold down the pressure under all conditions and are relatively unstable as compared with the cadmium amalgam.

The inert gases, neon, helium, argon, etc., can 75

be used where long tube life is not a primary requisite.

As the exact spacing of the grids to the cathode and especially of the control grid to the cathode is dependent upon the vapor pressure in the tube under maximum operating conditions, it will be seen that the choice of the ionizing medium is quite important. Naturally, the pressure will vary with the size of the bulb, power dissipated in the tube and location of the tube with respect to associated apparatus, as well as in relation to the kind of ionizing medium used.

In the typical tube described in my co-pending application bearing Serial Number 669,503, in which mercury vapor derived from pure mercury is used, and with a 2.5 watt cathode heater loss, the cathode fall space was such that the control grid was spaced at a distance approximately only .010" from the cathode. Whereas, in the tube of this invention, using a bulb of identical capacity, with an ionizing medium composed of approximately eighty per cent cadmium and twenty per cent mercury, the control electrode can be spaced .040" from the cathode with negligible ionization in the space therebetween. The space between the control grid and second grid and between second and outer grid is also of this magnitude.

This allows a less critical tube to be constructed and permits the use of a smaller bulb with decreased lag in the time required for the tube to come to equilibrium. The tube is also less sensitive to temperature variations.

Another advantage derived from the use of a cadmium-mercury amalgam in the tube, is that the plate voltage supply can be connected to the tube prior to the heating of the cathode without the destructive cathode disintegration due to localized arcing which is common in mercury vapor tubes. The vapor pressure is adequate to reduce space charge in the tubes but insufficient to allow the formation of localized arc discharge.

As to the proportions of mercury to cadmium, I have found that in a bulb having a capacity of 72 c. c. and a power dissipation or loss (combined cathode and anode) of 12 watts, that a compound or mixture composed of 20.4% mercury and 79.6% cadmium affords a satisfactory atmosphere source. It is a simple matter from these figures to determine the proportion of mercury to cadmium for a given size bulb and power loss to give an equivalent pressure.

There is an indication that the cadmium and mercury form a definite compound such as cadmium mercuride $HgCd_7$, for in volatilizing from the bulb container, the deposit on the inner wall of the bulb indicates the volatilization of the complete mixture. This would also account in part for the limited or restricted vapor pressure rise with temperature.

An essential difference between this cadmium-mercury amalgam tube and mercury vapor tubes of the prior art, is that the vapor pressure is just sufficient at normal operating conditions, to reduce the electron space charge, but insufficient to allow uncontrollable and localized discharge to the cathode. In combination with the other elements of my tube, this assists in reducing cathode disintegration to a minimum and allows long life, considered otherwise improbable with a vapor tube operating at a potential above the critical potential of the ionizable medium. With the grid coating and structure used, this cadmium amalgam tube allows a high voltage amplification factor and low impedance, resulting in a tube of ex-

ceptionally high mutual conductance and power sensitivity.

As in the tubes of my two aforesaid co-pending applications, the discharge should be confined to the space between the cathode emitting surface and the anode and directly through the grids. This is accomplished by providing blocking members, such as mica discs at the anode ends of the cathode emitting surface terminals, or by the use of a transverse electrical field of sufficient density at such terminals as provided in other co-pending cases.

Unless the current restricting facilities are provided at the ends of the cathode emission areas, the discharge will not flow through the grids but will flow to a section where the mean free path length is less than the electrode distances and a diffused uncontrollable discharge of high intensity obtains.

In order to afford a detailed description of one embodiment of my invention, reference is made to the accompanying drawing. In Fig. 1 the tube (1) houses cathode (2) which is coated with strontium and barium oxides (2a) to provide electron emission and which is almost entirely closed at the top to retain the heat. The cathode is supported by lead terminal (2b). Closely surrounding the cathode is control grid (3) supported by lead (3b) and support (3c) and which has an inside diameter about 80 mils greater than that of the outside diameter of the cathode. It has a winding of twenty-eight turns per inch along the cathode axis and extends for the length of the cathode emission surface. Surrounding this at a distance of approximately 50 mils is shield grid (4) which has the same number of turns as grid (3) but of a wider diameter. Grid (4) is supported by lead (4b) and support (4c). Surrounding grid (4) and spaced about 50 mils therefrom, is grid (5) of similar construction but wider diameter. Grid (5) is supported by lead (5b). The nickel anode (6) is of .750" diameter and at its terminals appear mica discs (8) and (9) for confining the discharge to the space between the cathode and anode and which help to maintain the elements in place. The mica discs are held in position by fasteners (8a) and (9a). The cathode is heated by tungsten heater wire (7) which has an integrally formed coating of aluminum oxide to insulate it from the cathode. The capsule (10) contains cadmium-mercury amalgam and a getter such as magnesium. (RF) is the radio frequency input source, energy from which is applied to the grid (3) and cathode (2) through the negative biasing portion of resistance (R_1) which is shunted across plate potential supply (E_p), allowing a positive potential to be applied to shield grids (4) and (5). At (C) is the output condenser for the anode potential supply and at (S) a translating device, such as a loud speaker.

While the cathode shown is indirectly heated, a directly heated type may, of course, be used.

The assembled tube should be completely degassed and the alkaline earth oxides broken down to their active form as is general practice, the magnesium getter and the mercury amalgam pill being discharged into the tube.

The third grid potential can be varied within limits so as to be positive or negative with respect to the second grid.

In operation, the cathode (2) is raised to emission temperature, and electrons are discharged therefrom. The control grid (3), being located within the dense electron field immediately adja-

- cent the cathode, exerts an electrostatic control on these electrons. As this grid is negatively biased, the plate current is held at a low value. The shield grid (4) is positively charged to prevent ionic currents from discharging to the control grid (3) and to reduce initial tube impedance. The control grid (3) is in an area where there is negligible visible ionization. The shield grid (4) is maintained at a positive potential. Grid (5) surrounding grid (4) being itself positively charged, reduces the necessary positive charge on grid (4), and allows a lowered impedance.
- When a radio frequency potential is applied to the grid circuit, there is a large plate current flow in proportion to the positive half of the superposed radio frequency oscillation. As this control is of a uniformly graduated nature, a rectified reproduction in the plate circuit occurs. A power output many fold that obtained in a pure vacuum tube is obtainable in a tube of the same volume and with increase sensitivity, when used as a detector. As so used, the tube permits the operation of radio receivers without the use of audio amplifier tubes.
- 25 While most of the above description of the tube relates to its employment as a detector, it may, however, be used as a tube having a very high power sensitivity.
- The tube of my invention when used as a detector can to advantage, for some special conditions have its control grid biased to a low negative voltage so as to give an initial control of the current flow from the anode and due to the positive component of the applied radio frequency potential it may allow the control grid during operation to become slightly positive. The use of the cadmium amalgam allows such an operating condition, whereas, if mercury vapor alone were used with a neutral or positively biased grid, the discharge would become so intense as to arc.
- Since certain changes in carrying out the construction of the tube and its components, and obvious substitutions can be made in the arrangement of the elements and in the materials without departing from the scope of the invention, such as placing two or more amplifier units in one envelope, substituting perforated or slotted control and shielding electrodes for the wound type described, etc., it is intended that all matters contained in the above description or shown in the accompanying drawing shall be interpreted as illustrative and not in a limiting sense.
- Having described my invention, what I claim as new and desire to secure by Letters Patent, is:
1. An ionic discharge amplifier comprising a sealed envelope containing an ionizing medium, an electron emission cathode, an anode spaced from the cathode at a distance beyond the free mean path length, and a plurality of control elements located in the space intermediate the cathode and anode, at least one of said control elements being spaced from the cathode at a distance less than the mean free path length of the electrons in the ionizable medium.
  2. An ionic discharge amplifier as described in claim 1 in which the ionizing medium is formed from a mercury amalgam.
  3. An ionic discharge amplifier as described in claim 1 in which the ionizing medium is formed from a cadmium-mercury amalgam.
  4. An ionic discharge amplifier as described in claim 1 in which the cathode is of the indirectly heated type.
  5. An ionic discharge amplifier as described in
- claim 1 in which the control elements are of the wire wound type.
6. An ionic discharge amplifier as described in claim 1 in which the anode surrounds the cathode and control elements along their length.
7. An ionic discharge amplifier comprising a sealed envelope containing an ionizable medium, a cathode having an electron emission surface, a control grid surrounding said cathode along its length and positioned at a distance therefrom no greater than the limits of the space of controllable cathode electron emission, a first shield grid surrounding said control grid along its length for shielding said control grid from ionic currents tending to discharge thereto, a second shield grid surrounding said first shield grid along its length, and an anode surrounding said cathode and grids along their length and spaced at a distance from the outer grid sufficient to allow ionization in the space therebetween, and means at the ends of the cathode electron emission area to direct and confine the electron discharge through the control grid.
8. An ionic discharge amplifier as described in claim 7 in which the control grid is adapted to be negatively biased in respect to the cathode.
9. An ionic discharge amplifier as described in claim 7 in which the first shielding grid is adapted to be positively charged in respect to the cathode and control grid.
10. An ionic discharge amplifier as described in claim 7 in which the grids are of the wire wound type.
11. An ionic discharge amplifier as described in claim 7 in which the ionizable medium is a mercury amalgam.
12. An ionic discharge amplifier as described in claim 7 in which the ionizing medium is formed from cadmium and mercury.
13. An ionic discharge amplifier as described in claim 7 in which the ionizing medium is formed from a cadmium-mercury amalgam in which the cadmium predominates.
14. An ionic discharge amplifier as described in claim 7 in which the cathode is of the indirectly heated type.
15. An ionic amplifier comprising a sealed envelope containing an electron emission cathode, a control grid, an anode and an ionizable medium formed from a cadmium-mercury amalgam having a preponderance of cadmium and having a mercury content not substantially lower than 20.4%.
16. An ionic amplifier comprising a sealed envelope containing an electron emission cathode, a control grid, an anode and an ionizable medium having a restricted pressure rise with increase in temperature and formed from a cadmium-mercury amalgam having a preponderance of cadmium and having a mercury content not substantially lower than 20.4%.
17. An ionic amplifier comprising a sealed envelope containing an electron emission cathode, an anode and an ionizable medium formed predominantly from cadmium but having a mercury content not substantially lower than 20.4%.
18. An ionic discharge amplifier comprising a sealed envelope, an ionizable medium, a thermionic cathode, an anode and a plurality of grid members positioned in the space intermediate the cathode and anode, at least one of said grid members having a coating composed of carbon and aluminum.
